[57] **CLAIM**

The ornamental design for an exterior facing body panel support for a mounting for automobile headlight assembly, as shown and described.

DESCRIPTION

FIG. 1 is a front view of an exterior facing body panel support for a mounting for automobile headlight assembly according to my novel design;

FIG. 2 is a top view of an exterior facing body panel support for a mounting for automobile headlight assembly according to my novel design;

FIG. 3 is a left side view of an exterior facing body panel support for a mounting for headlight assembly according to my novel design;

FIG. 4 is a right side view of an exterior facing body panel support for a mounting for automobile headlight assembly according to my novel design;

FIG. 5 is a bottom view of an exterior facing body panel support for a mounting for automobile headlight assembly according to my novel design; and,

FIG. 6 is a perspective view from the front left of an exterior facing body panel support for a mounting for automobile headlight assembly according to my novel design.

The dash line showing depicts environment and is not part of the claimed design. The design envisioned will contain a second portion whose image is mirror symmetrical to this item. The embodiment shown is the left side portion.
